UNITED STATES PATENT OFFICE

2,274,008

ELECTRICAL COMMUNICATION APPARATUS

Walter Spiegel, New York, N. Y.

Application December 26, 1939, Serial No. 310,906

11 Claims. (Cl. 179—1)

My invention relates to improvements in electrical intercommunication apparatus, and more particularly to switching circuits for such apparatus.

The object of the invention is to provide a simple, efficient, switching arrangement for communicating apparatus whereby any master station will be enabled to transmit and receive from any other master or any sub-station in the system. A further object is to enable any sub-station to selectively transmit to and receive from any master station in the system.

In devices of this nature it has heretofore been impossible for any particular sub-station to communicate with any but one master station in the system, and it has been desirable to allow any sub-station to select and communicate with any master station in the system, though it has been impossible to do so heretofore.

Embodiments of the invention are shown in the accompanying drawings in which: Figure 1 is a schematic wiring diagram of a master station having a two stage audio amplifier and embodying my switching arrangement. Figure 2 is a diagrammatic view of a sub-station employing my switching circuit. Figure 3 is a block diagram of several masters and several sub-stations connected to one another.

Referring to Figure 1 of the drawings, a two stage audio amplifier is shown adapted to be used as a master station for intercommunicating apparatus. 1 is a rectifying tube connected to a source of current in the usual manner. Choke coil 2 and condensers 3 comprise a filter system for smoothing out the pulsations or ripples of the rectified current output of tube 1. The rectified current after passing through said filter system is used to energize the plates and screens of tubes 4 and 5. The filaments of tubes 1, 4, and 5 are connected in series and are connected to the source of current, through resistance 6, which drops the voltage down to that desired for energizing said filaments. As the amplifier itself is of conventional design, further explanation will be unnecessary.

In using the master station shown in Figure 1, to transmit to another master, the operation is as follows: 1 is a permanent magnet speaker, and when spoken into, its diaphragm vibrates and sets up electrical vibrations in coil 8, which are fed through line 9 to hook 10 and from hook 10 through line 11 to switch 12, and contact 12¹, and from contact 12¹ to one side of the primary of transformer 13, and from the other side of transformer 13 to lines 14 and 15 and to

condenser 16, and by line 17 to ground 18. The current is induced in the secondary of transformer 13, and is amplified in the usual manner by tubes 4 and 5 and their associated circuits. The amplified current is induced from the primary of transformer 19 to its secondary winding, and through line 19¹ to contact 20 of switch 21, and from switch 21 by line 22 to the selective switch 23, and by contact 24 to line 25 and binding post 26. The other side of the secondary of transformer 19 is fed through lines 27 and 28 to ground 18¹ and from ground 18¹ to ground 18, to line 17, condenser 16, line 15, common line 14 and to binding post 27, which latter and binding post 26 may be connected to a sub-station.

When transmitting from the master shown in Figure 1 to another master station, switches 21, 12 and 30 are thrown to contacts 31, 32, and 33 respectively, and when talking into speaker 7, impulses are set up in line 9, through hook 10, line 11, switch 12, contact 32, and by line 33¹ to contact 31 of switch 21, and from switch 21 by line 22 to switch 23, and by contact 34, through line 35 to terminal 36, and from terminal 36 to the particular master station desired and back to terminal 27, through common line 14, and by line 15 to condenser 16, and line 17 to ground 18, line 28, line 27 and to the opposite end of the voice coil.

When listening to the master shown in Figure 1, the switches 21, 12, and 30 are thrown to contacts 37, 38, and 39, and the impulses transmitted from the transmitting station are fed to terminal 40, by line 41 to contact 42 of switch 23, and from the latter by line 22 to switch 20, and from contact 37 of switch 20 to the primary of transformer 13, and from the opposite end of said primary by line 14 to terminal 27 and back to the transmitting station.

The impulses set up in the secondary of the transformer 13 are amplified in the amplifier and are fed from the secondary of transformer 19 to line 19¹, contact 38 of switch 12, by line 43, and from switch 12 by line 11 to hook 10, and line 9 to one end of voice coil 8, and from the other end of voice coil 8 to ground 18¹ by lines 27 and 28. From ground 18, by line 17 to condenser 16, common line 14, line 15, to terminal 27, by common line 14 and line 15.

Switches 21, 12, and 30 may be actuated by a common means as shown, or by other common means.

In each instance I have used a successive contact of switch 23 leading to successive terminals

in order, to show that the switch is a selective device. It is to be understood that each terminal is to be used for one line of a distant station, both when transmitting and receiving, and the other line of each station is attached to terminal 27.

When receiving by sub-station shown in Figure 2, impulses from the transmitting station are brought to any of the terminals of selector switch 45 and from there by lines 46 and 47 to hook 48, lines 49 and 50 to voice coil 51 by lines 52 and 53 to common terminal 55 and back to the transmitting station. When using the sub-station to transmit switch 56 is thrown to contact 57 and impulses set up in coil 51 are fed to switch 56, by line 58, and contact 57, to switch 45, by line 46, and from said switch to any desired terminal, and from there to the station being transmitted to and back to voice coil 51 through terminal 55 and common line 53.

Master stations 60 to 62 inclusive and sub-stations 63 to 65 inclusive are shown suitably connected in Figure 3.

Of course it will be understood that various modifications may be made without departing from the spirit of the invention as claimed.

I claim:

1. In an electric communication system of the character described, a master station having electronic amplifying means, a translating device employed alternately as speaker and microphone, said master station including switching means for allowing operation of the translating device with or without the amplifying means in the circuit.

2. In an electric communication system of the character described, a master station having electronic amplifying means, switching means for disconnecting the amplifier when transmitting to stations equipped with amplifiers and for connecting the amplifier in circuit when transmitting to stations without amplifiers, said switching means being adapted to connect the amplifier in the circuit when receiving from any station.

3. An electric communication system of the character described, a master station having an electronic amplifier, switching means for connecting the amplifier when transmitting to any station, said switching means being adapted to disconnect the amplifier from the circuit when receiving from stations employing amplifiers.

4. An electric communication system of the character described including a plurality of the master stations, each of said master stations employing amplifiers, a plurality of sub-stations, said substations not employing amplifiers, and means for selectively communicating by any sub-station with any master station.

5. An electric communication system of the

character described including a plurality of the master stations, said master stations employing amplifiers, a plurality of sub-stations, said sub-stations not employing amplifiers, means for selectively communicating by any master with any sub-station, and means for selectively communicating by one station with another.

6. An electrical communication system of the character described; having a plurality of master-stations, each master-station including amplifiers; a plurality of sub-stations, said sub-stations being minus amplifiers; and means for selectively communicating by any sub-station with any master station.

15 7. An electrical communication system of the character described; having a plurality of master-stations, each master-station including a vacuum tube amplifier; a plurality of sub-stations; and means for selectively communicating by any desired master-station with any sub-station to the exclusion of any other station.

20 8. An electrical communication system of the character described; having a plurality of master-stations and one or more sub-stations; and means for selectively communicating by any one master-station with any other master-station to the exclusion of all other stations.

25 9. An electrical communication system of the character described; having a plurality of master-stations, and one or more sub-stations; and means for selectively communicating by any one master-station with any other station, said means including electrical switching means for intermittent transmission and reception.

30 10. An electrical communication system of the character described; having a plurality of master-stations, each master-station including amplifying means; one or more sub-stations; and means for selectively communicating by any sub-station with any master-station, said means including electrical switching means for selectively connecting any sub-station with any desired master-station to the exclusion of all other stations.

35 11. In a communication system of the character described; a plurality of master-stations, each master-station including an amplifier and translating device, said translating device adapted to be employed alternately as a speaker and microphone; one or more sub-stations; switching means for selectively transmitting and receiving by any master-station to and from any other master or sub-station, said switching means being adapted to connect said translating device to the output circuit of said amplifier when receiving from a sub-station and to disconnect said translating device from said amplifier when receiving from a master-station.

WALTER SPIEGEL.
